REFRIGERATION

Nils Widell, Stockholm, Sweden, assignor, by
mesne assignments, to Servel, Inc., Dover, Del.,
a corporation of Delaware

Application March 26, 1935, Serial No. 13,013
In Germany March 29, 1934

18 Claims. (Cl. 62—5)

My invention relates to refrigeration and more particularly to control of refrigeration temperature.

It is an object of my invention to provide for control of refrigeration temperature without affecting the process or apparatus involved in producing the refrigeration.

It is another object to provide for temperature control of a refrigerator having an uncontrolled cooling source.

A further object is to provide for temperature control of a refrigerator including a continuous absorption refrigeration apparatus having a substantially constant heat input.

15 My invention, together with the objects and advantages thereof, will be fully understood upon reference to the following description and accompanying drawing in which:

The figure shows more or less schematically a 20 refrigerator embodying my invention.

Referring to the drawing, a refrigerator cabinet 10 provides a thermally insulated storage compartment 11 accessible by means of a door 12. In the upper part of the refrigerator compartment 25 11 is a cooling element 13 of an absorption refrigeration apparatus like that, for instance, disclosed in U. S. Patent 1,609,334 to von Platen et al. In the refrigerator cabinet 10 there is also an apparatus compartment 14 in which are located the other parts of the refrigeration apparatus including a generator 15. The generator 15 is of a vertical type comprising a vertically elongated vessel through which extends a heating flue 16. The generator 15 is heated by a burner 17 disposed so 30 that the burner flame is projected into the lower end of the heating flue 16. The burner 17 may be of any desired type as, for instance a kerosene or alcohol burner.

The operation of the refrigeration apparatus 40 may be fully understood by reference to the disclosure of said U. S. Patent 1,609,334. Briefly, however, an apparatus of this general type includes a generator and an absorber through and between which circulates a solution of refrigerant, such as ammonia, in an absorption liquid, such as water. In the generator, vaporous refrigerant is 45 expelled from solution by heat. The vaporous refrigerant is liquefied in a condenser and the liquid conducted to an evaporator. The evaporator is 50 interconnected with the absorber for circulation therebetween of an inert auxiliary gas as, for instance, hydrogen. In the evaporator, liquid refrigerant evaporates and diffuses into the hydrogen, producing a refrigeration effect. In the absorber, refrigerant vapor is absorbed into solution out of

the inert gas, thus maintaining the partial pressure of refrigerant vapor sufficiently low to permit continued evaporation of refrigerant in the evaporator. It will be understood that the nature of the refrigeration apparatus or process is not the 5 subject of this invention.

Again referring to the drawing, air in the refrigerator compartment 11 is cooled by circulation in thermal exchange relation with the evaporator or cooling element 13. If operation of the 10 refrigeration apparatus, of which the cooling element 13 is a part, is not controlled, as in case the burner 17 is an ordinary continuously operating oil burner, the temperature in the refrigerator storage compartment 11 may be reduced below a 15 minimum value desirable for proper preservation of foodstuffs or other substances which may be stored in the refrigerator. Even through the refrigeration apparatus may be operated with the cooling element 13 at a substantially constant 20 temperature, it will be understood that the temperature in the storage compartment 11 is subject to considerable change depending upon variations in heat leakage upon change in air 25 temperature outside of the refrigerator and introduction into the storage compartment of material containing various quantities of heat.

In order to prevent the temperature in the storage compartment 11 from becoming lower than a given value, I provide a vaporization-condensation structure including a condenser portion 18, a vaporization portion 19, an accumulation vessel 20, and a thermostatically operated valve 21. The condenser portion 18 is located within the refrigerator storage compartment 11 30 and is provided with a suitable heat transfer surface formed by fins 22. The vaporization portion 19 may advantageously be formed as a pipe coil and located around the generator heating flue 16 at a point above the generator 15. The 35 upper end of the coil 19 is connected by a conduit 23 to the upper part of the condenser 18. The lower end of the vaporization coil 19 is connected to the accumulation vessel 20. The lower part of the condenser 18 is connected to the accumulation vessel 20 by means of a conduit 24. The thermostatically operated valve 21 is 40 constructed and arranged to control the flow of liquid from the condenser 18 through the conduit 24 into the accumulation vessel 20. The 45 lower end of the vaporization coil 19 is connected to the accumulation vessel 20 by means of a conduit 24. The thermostatically operated valve 21 is 50 constructed and arranged to control the flow of liquid from the condenser 18 through the conduit 24 into the accumulation vessel 20. The 55 valve 21 may be of any desired type as a hermetically sealed valve operated by an expansible fluid thermostat including a sensitive bulb 25 which is located in the refrigerator storage compartment 11. Such a thermostatic valve is

shown in an application for Letters Patent Serial Number 332,162 of W. T. Hedlund, filed January 12, 1929, now Patent No. 2,044,609, granted June 16, 1936. For the present purpose, the valve 5 would be arranged to open rather than close upon decrease in temperature.

The just described vaporization-condensation member or circuit contains a suitable fluid adapted to condense to liquid in the condenser 18 and 10 vaporize into gas in the coil 19. Heat of vaporization is added to the fluid in the coil 19 and heat of condensation is given up by the fluid in the condenser 18, wherefore the fluid may be referred to as a heat transfer fluid. The thermostatic valve 21 is preferably adjustable, as known, 15 and is arranged to open when a desired minimum temperature is reached in the refrigerator storage compartment 11 in which the thermostat bulb 25 is located. It will be understood that 20 the vaporization coil 19 may be heated in any desired manner. It is desirable to maintain the temperature of the vaporization coil 19 at a temperature above that of the air and it is for this purpose arranged in thermal transfer relation with the flue 16 above the generator 15 where it is subject to the temperature of the combustion gas.

In operation, assume that the temperature in the refrigerator compartment 11 has reached a 30 predetermined minimum value as, for instance, 34° F. The valve 21 has been adjusted to open at this temperature so that liquid, which has been formed by condensation in the condenser 18, flows through conduit 24 into the accumulation vessel 20. The liquid flows from the accumulation vessel 20 into the lower end of the vaporization coil 19 which is heated by the flue 16. The liquid is vaporized in coil 19 and the vapor flows through conduit 23 into the condenser 18. In this manner, heat is conducted by the heat transfer fluid from the flue 16 into the refrigerator storage compartment 11. This influx of heat into the compartment 11 prevents the temperature therein from decreasing below 45 the desired minimum value of 34° F. Upon continued influx of heat, the temperature in the compartment 11 rises above the said value of 34° F. so that the thermostatic valve 21 closes, cutting off flow of liquid from the condenser 18 to the 50 accumulation vessel 20. Liquid continues to vaporize in the coil 19 until there is no more fluid in liquid phase in this part of the device, whereupon there is no further transfer of heat into the storage compartment.

55 By heating the vaporization coil 19 more or less directly by the source of heat input, the burner 17, I maintain a greater temperature difference between the vaporization and condensation portions of what may be called the heat 60 influx device and thereby obtain greater heat transmission into the refrigerator than if the vaporization coil 19 were subject to the temperature of the air outside of the refrigerator as is possible. This greater temperature differential 65 between the vaporization and condensation portions of the cycle makes possible a smaller condenser, that is, the necessary heat transfer surface of the condenser 18 is an inverse function of the temperature differential between the condenser 18 and the vaporization coil 19. I may also 70 make the vaporization coil 19 of sufficiently small internal diameter so that heated liquid is raised by thermal siphonic action upwardly through the coil 19 and conduit 23 into the condenser 18. In this case the heat transferred is the heat of the

liquid between the temperatures of the condenser 18 and the vaporizing coil 19 plus the heat of vaporization of the vapor which causes the liquid circulation.

It will be understood that various changes may 5 be made within the scope of my invention which is therefore not limited to that which is shown in the drawing and described in the specification but only as indicated in the following claims.

What is claimed is:

1. In a refrigerator having a thermally insulated storage compartment, a refrigeration apparatus including a cooling element in said compartment, and a vaporization-condensation structure including a condenser in said storage 15 compartment, said structure forming a circuit separate from said refrigeration apparatus, means for regulating flow of fluid in said structure responsive to temperature in said storage compartment, and a common source of heat for 20 said refrigeration apparatus and said vaporization-condensation structure.

2. Controlling a refrigerator by heating a refrigerant to be condensed and evaporating the refrigerant, and off-setting the cooling effect 25 thereby instigated by vaporizing a separate fluid due to the same heat source to a temperature above atmospheric and condensing the last named fluid to reject heat and provide a rise of temperature counteracting said cooling effect. 30

3. Controlling a refrigerator having a space to be cooled by heating a refrigerant to be condensed and evaporating the refrigerant in heat exchange relation with the space to be cooled, offsetting the cooling effect thereby instigated by 35 vaporizing a separate fluid due to the same heat source to a temperature above atmospheric and condensing the last named fluid to reject heat and provide a rise of temperature counteracting said cooling effect, and controlling the extent of 40 offsetting heat rejection in response to temperature of the space to be cooled.

4. In a refrigerator having a thermally insulated compartment, fluid containing absorption refrigeration apparatus to produce refrigeration 45 and having a cooling element arranged to cool said compartment, a heated portion outside of said compartment and containing refrigerant fluid in an absorbent, a heat source for said heated portion, means whereby heating of said 50 heated portion causes cooling of said cooling element, and means providing a fluid path, in addition to the paths of flow of fluid in the apparatus utilized to produce refrigeration, for conducting heat from said heat source into said 55 compartment, whereby said heat source serves as a common heat source for the production of refrigeration in said compartment and transfer of heat thereto.

5. In a refrigerator having a storage compartment in which a cooling effect is produced, a vaporizer located outside said compartment for vaporizing fluid, a member arranged in thermal transfer relation with said compartment, means providing a path of flow for vaporized fluid from 65 said vaporizer to said member to conduct heat directly into said compartment, means to provide a liquid barrier between the vaporizer and said member whereby the direct conduction of heat to said compartment through said path can be 70 prevented, and means for causing the flow of vaporized fluid to take place through said path by change of condition of the liquid barrier.

6. In the art of refrigeration with an absorption refrigerating system including vaporizing 75

fluid at a place of vapor expulsion, condensing vaporized fluid to liquid at a place of condensation, and flowing liquid from the place of condensation into thermal transfer relation with a 5 medium to be cooled and there vaporizing the liquid to produce a refrigerating effect, the improvement which consists in simultaneously flowing vaporous fluid into thermal transfer relation with said medium to be cooled and there condensing the fluid to counteract said refrigerating effect, and controlling said flow of vaporous fluid to control said counteraction.

7. In a refrigerator as set forth in claim 4, means for controlling flow of fluid in said path. 15 8. In a refrigerator having a thermally insulated storage compartment, continuous absorption refrigeration apparatus including a generator, a cooling element in said compartment, and a substantially constant source of heat for causing 20 expulsion of refrigerant vapor from an absorbent in said generator the expelled refrigerant vapor being liquefied in said apparatus and flowing to said cooling element for vaporization therein, and a vaporization-condensation structure 25 including a condenser in said storage compartment, a vaporizer arranged to be heated by said source of heat, conduits connecting said condenser and vaporizer and forming therewith a circuit adapted to contain a volatile fluid, and 30 a thermostatically operated valve for regulating flow of fluid in said circuit responsive to temperature in said storage compartment.

9. In a refrigerator having a thermally insulated storage compartment, continuous absorption refrigeration apparatus including a generator, a cooling element in said compartment, and a substantially constant source of heat for causing 35 expulsion of refrigerant vapor from an absorbent in said generator, the expelled refrigerant vapor being liquefied in said apparatus and flowing to said cooling element for vaporization therein, and a vaporization-condensation structure including a condenser in said storage compartment, a vaporizer without said compartment, conduits connecting said condenser and vaporizer and forming therewith a circuit adapted to contain a volatile fluid, and means for 40 regulating flow of fluid in said circuit responsive to temperature in said storage compartment.

10. In a refrigerator having a thermally insulated storage compartment, absorption refrigeration apparatus including a cooling element constructed and arranged for cooling said compartment, and a generator in which refrigerant vapor is expelled out of an absorbent by heating, the 45 expelled refrigerant vapor being liquefied in said apparatus and flowing to said cooling element for vaporization therein, and means for controlling the temperature of said compartment including a first fluid containing member constructed and arranged for heating said compartment, a second heated fluid containing member outside of said compartment, connections for circulation of heat transfer fluid between said members, and means operable to prevent flow of fluid to said heated member.

11. A refrigerator as set forth in claim 10 in which said flow preventing means is automatically operative responsive to temperature in said compartment.

12. A refrigerator as set forth in claim 10 in which said fluid containing members and connections constitute a vaporization-condensation structure.

13. A refrigerator as set forth in claim 10 in which said fluid containing members and connections constitute a vaporization-condensation structure, and said flow preventing means is thermostatically operated responsive to temperature in said compartment and causes liquid to remain in said first member forming the condensation portion of said structure. 5

14. In a refrigerator cooled by a continuous absorption type refrigeration apparatus comprising a plurality of interconnected parts including a cooling element and a generator and having a substantially constant source of heat for causing expulsion of refrigerant vapor from an absorbent in said generator, the expelled refrigerant vapor being liquefied in said apparatus and flowing to said cooling element for vaporization therein, that improvement which consists in controlling the refrigeration temperature by taking heat from said source and transferring the heat 10 into the refrigerator at a rate in accordance with the temperature to be maintained with the aid of a vaporization-condensation structure having a condensation portion in said refrigerator and a vaporization portion outside of said refrigerator 15 and heated by a part of said apparatus.

15. A refrigerator comprising a cabinet, fluid containing absorption refrigerating apparatus for cooling said cabinet comprising a plurality of interconnected parts including a generator in 20 which refrigerant vapor is expelled out of an absorbent by heating and an evaporator into which such expelled refrigerant flows after being liquefied, means to heat said generator above atmospheric temperature, a heat rejecting condenser situated so that rejected heat is transferred to a part of the refrigeration apparatus to counteract cooling effect of said refrigerating apparatus, and means utilizing said generator heating means for feeding fluid to be condensed 25 to said condenser.

16. A refrigerator comprising a cabinet, fluid containing absorption refrigerating apparatus for cooling said cabinet comprising a plurality of interconnected parts including a generator in 30 which refrigerant vapor is expelled out of an absorbent by heating and an evaporator into which such expelled refrigerant flows after being liquefied, means to heat said generator above atmospheric temperature, a heat rejecting condenser situated so that rejected heat is transferred to a part of the refrigeration apparatus to counteract cooling effect of said refrigerating apparatus, means utilizing said generator heating means for feeding fluid to be condensed 35 to said condenser, and temperature responsive means for controlling the feed for fluid to said condenser.

17. In a refrigerator having a thermally insulated compartment, absorption refrigeration apparatus including a cooling element arranged for cooling said compartment and a generator located outside said compartment and in which refrigerant vapor is expelled from an absorbent by heating, the expelled vapor being liquefied 45 in said apparatus and flowing to said cooling element for vaporization therein, means for heating said generator, and means for conducting heat derived from said first means into said compartment.

18. In a refrigerator as set forth in claim 17, 50 means for controlling operation of said heat conducting means.
